FIRE EXTINGUISHER DISCHARGE DEVICE

Frank B. Allen, Towaco, N. J., assignor to C-O-Two Fire Equipment Company, Newark, N. J.

Application January 27, 1953, Serial No. 333,402

5 Claims. (Cl. 169—11)

The present invention relates to fire extinguishing, and particularly to an improved discharge device for carbon dioxide extinguishing fluid.

In using carbon dioxide as a fire extinguishing agent, in some systems it is stored at high pressure in containers at atmospheric temperature, and in other systems it is stored at a sub-atmospheric pressure in refrigerated containers. In both cases the pressure is such that if the fluid is discharged without a suitable velocity-reducing device, air is entrained to reduce the effectiveness of the carbon dioxide. Furthermore, the velocity might be so great as to cause the scattering of burning combustible material.

Heretofore, various types of discharge devices have been provided to attain the desired result, among which is the construction disclosed in S. E. Allen et al. Patent No. 1,993,696, issued March 5, 1935. The present invention is an improvement over that disclosed in the Allen et al. patent in that a somewhat more simplified construction is disclosed.

Prior constructions have provided a discharge device including a closed end tubular member extending into the shield, the side wall of the tubular member being provided with a plurality of orifices. Such constructions, when used on extinguishers of small discharge capacity, necessitate the use of screening to protect the small orifices from clogging by mill scale or other matter which may be in the piping system and carried by the discharging fluid.

An object of the present invention is to provide a discharge device which is simple and economical in manufacture, efficient in operation and durable in use.

In accordance with the invention this is accomplished by providing a discharge device in which an orifice is placed at the end of the valve body and means is provided for redirecting and expanding the fluid before discharging it into the shield. By reason of the turbulence and expansion, a short shield may be used for the further expansion of the fluid and for directing the fluid.

Other objects and advantages of the invention will be apparent from the following description and from the accompanying drawing which shows, by way of example, an embodiment of the invention.

In the drawings:

Figure 1 is a sectional view of a fire extinguisher discharge device in accordance with the invention.

Figure 2 is an end view looking from right to left of Figure 1 in the direction of the discharge.

Figure 3 is an outer end view of the inner body member.

Figure 4 is a side view of the inner body member with a portion thereof broken away to show the passages therethrough.

Figure 5 is a side view of the outer body member with a portion thereof broken away to show the passages therethrough.

Figure 6 is an end view of the outer body member looking from right to left in Figure 5.

2

Referring to the drawings, there is shown in Figure 1 a fire extinguisher discharge device 1 in accordance with the invention including an outer body member 2, an inner body member 3, and a discharge shield 4.

5 The outer body member 2 may be made from tubular stock and has its outer surface 6 faced for engagement by a wrench to secure the body member in position on piping for the conventional carbon dioxide fire extinguisher system. A passage 7 extends through the body member 2 and has a reduced portion 9 made with a threaded surface for engagement of the inner body member. By reducing the diameter of the passage, a shoulder 10 is made to limit the outward movement of the inner body member 3. The inner end of the passage 7 is threaded as indicated at 11 for a piping connection. An axially-extending flange 12 is formed on the outer end of the body member 2, the inner surface of the flange 12 having a somewhat greater diameter than the outer diameter of the inner body member 3. A shoulder 14 is provided at the base of the flange 12 and is preferably made with a slight undercut as may be seen at 15.

The inner body member 3 is of generally tubular shape with a closed end wall 17. A plurality of transversely-extending orifices 20 are formed adjacent the end wall 17. 25 A passage 21 extends through the inner body member 3, the passage being reduced in size as indicated at 22 to provide an orifice opening of predetermined diameter, the diameter of the orifice opening being less than the diameter of the transversely-extending passages 20 so that there is an expansion of the fluid passing through the orifice 22 as it passes through the passages 20. Outer surface 24 of the inner body member 3 is threaded for engagement with the threaded surface 11 of the outer body member. Inner end 25 of the inner body member is enlarged to provide a head to engage with the shoulder 10 of the outer body member, slots 26 being provided for engagement by a tool to tightly position the inner body member in position in the outer body member.

The discharge shield 4 is preferably made with straight side walls 30, the outer end being flanged as indicated at 31 to secure the shield in position over an opening, conventional flange-securing means (not shown) being used to hold the shield in position. The inner end of the shield 4 is curved inwardly as indicated at 32, an opening being made in the inner end of the shield of a diameter to slip over the flange 12 of the inner body member 2, the curvature of the shield fitting the undercut surface of the body member 2. The flange 12 is turned outwardly against the edge of the opening in the shield 4 to hold the shield in position.

In using a discharge device in accordance with the invention, it is attached to the piping system of a carbon dioxide fire extinguishing system. Upon a discharge of the fire extinguishing fluid, the fluid is metered in the orifice 22 and slightly expanded in the transversely-extending passages 20, the stream then further expanding inside the inner end 32 of the shield 4. A region of intense cold temperature is provided about the inner member 3 lowering the temperature of the issuing stream as it passes through the orifice 22 and the expansion passages 20. 55 By reason of the expansion in the passage 20, the temperature of the issuing fluid is lowered somewhat so that carbon dioxide snow is formed at the end of the passages 20 or possibly slightly inward of the outward end of these passages. Thus, an efficient carbon dioxide discharge device is provided in which the shield 4 may be of comparatively small size and short in length. The construction is economical in construction, efficient in operation and durable in use.

70 While the invention has been described and illustrated with reference to a specific embodiment thereof, it will be understood that other embodiments may be resorted

to without departing from the invention. For example, while the transversely-extending passages 20 have been shown as having a length determined by the diameter of the inner body member 3, expansion tubes with straight or flaring walls may be inserted in the passage extending the length thereof so as to provide for a still further expansion of the issuing fluid before it is discharged at the outer ends of these transversely-extending tubes. In this case in some constructions it might be preferable to enlarge the diameter of the shield 4. Therefore, the form 10 of the invention set out above should be considered as illustrative and not as limiting the scope of the following claims.

I claim:

1. A fire extinguisher discharge device comprising a shield having a partially closed end forming a shield base with an opening of a predetermined diameter, a compact body member for the support of the shield and including an outer conduit connecting tubular member having a passage therethrough, the outer tubular member having a threaded inner surface and a portion of enlarged diameter defining a shoulder, axially-extending flange means extending from the body member at one end thereof and of an outer diameter to fit within the opening in the shield, the edge of the flange turned over the edge of the opening in the shield holding the shield in position, and an inner tubular member having a threaded outer surface for engagement with the threaded inner surface of the outer tubular member, the inner tubular member having a closed end, the open end of the inner tubular member of enlarged cross-section to provide a shoulder adapted to abut against the shoulder of the outer tubular member, the tubular member formed with a plurality of transversely extending discharge openings positioned adjacent the closed end, the passage in the inner tubular member adjacent the discharge openings of restricted cross-section forming an orifice of a predetermined size, the area of the orifice opening less than the area of the discharge openings providing for expansion of the fluid after it has passed through the orifice but before being discharged into the shield, the closed end of the inner tubular member positioned inside the base of the shield in a region of low temperature thereby providing a preliminary cooling and expansion of the issuing stream before it is redirected and further expanded in the shield.

2. A fire extinguisher discharge device comprising a shield having a partially closed end forming a shield base with an opening of a predetermined diameter, a compact body member for the support of the shield and including an outer tubular member having a passage therethrough, the outer tubular member having a threaded inner surface, axially-extending flange means extending from the body member at one end thereof and of an outer diameter to fit within the opening in the shield, the edge of the flange turned over the edge of the opening in the shield holding the shield in position, and an inner tubular member having a threaded outer surface, the inner tubular member having a closed end and formed with a plurality of transversely extending discharge openings positioned adjacent the closed end, the passage in the inner tubular member adjacent the discharge openings of restricted cross-section forming an orifice of a predetermined size, the area of the orifice opening less than the area of the discharge openings providing for expansion of the fluid

5 after it has passed through the orifice but before being discharged into the shield, the closed end of the inner tubular member positioned inside the base of the shield in a region of low temperature thereby providing a preliminary cooling and expansion of the issuing stream before it is redirected and further expanded in the shield.

3. A fire extinguisher discharge device comprising a shield having a partially closed end forming a shield base, a compact body member for the support of the shield and including an outer tubular member having a passage therethrough, shield securing means on the body member at one end thereof for the support of the shield, and an inner tubular member having a passage therethrough with a closed end and formed with a plurality of transversely extending discharge openings positioned adjacent the closed end, the passage in the inner tubular member adjacent the discharge openings of restricted cross-section forming an orifice of a predetermined size the area of the orifice opening less than the area of the discharge openings providing for expansion of the fluid after it has passed through the orifice but before being discharged into the shield, the closed end of the inner tubular member positioned inside the base of the shield in a region of low temperature thereby providing a preliminary cooling and expansion of the issuing stream before it is redirected and further expanded in the shield.

4. A fire extinguisher discharge device comprising a shield having a partially closed end forming a shield base, a compact body member supporting the shield and including an outer tubular member having a passage therethrough, and an inner tubular member having a passage therethrough with a closed end and having a plurality of transversely extending discharge openings positioned adjacent the closed end, the passage in the inner tubular member adjacent the discharge openings of restricted cross-section forming an orifice of a predetermined size less than the area of the discharge openings providing for expansion of the fluid after it has passed through the orifice but before being discharged into the shield, the discharge end of the inner tubular member positioned inside the base of the shield in a region of low temperature under discharge condition thereby providing a preliminary cooling and expansion of the issuing stream before it is redirected and further expanded in the shield.

5. A nozzle for a fire extinguisher discharge device comprising a body member having a passage therethrough, means closing an end of the passage, means forming a plurality of transversely extending discharge openings positioned adjacent the closed end, and means restricting the passage adjacent the discharge openings forming an orifice of restricted size less than the area of the discharge openings providing for expansion of the issuing fluid after it has passed through the orifice but before being discharged into the shield, thereby providing a preliminary cooling and expansion of the issuing stream before it is discharged from the nozzle.
